RELAY

John H. Horman, Tuckahoe, N. Y., assignor, by
mesne assignments, to Smaller War Plants Cor-
poration, New York, N. Y., a corporation of the
United States

Application June 11, 1943, Serial No. 490,449

6 Claims. (Cl. 200—1)

This invention relates to relays.

In a known type of relay, there is a contact arm pack in which a plurality of metal members or plates are superposed in parallel relation and are separated by insulating spacers and held against displacement by bolts from which the plates are insulated by insulating sleeves surrounding the bolts. Strips of Bakelite or other similar material have been used as spacers and the plates have been continuous between the bolts.

An object of this invention is to reduce the capacity effect between successive members in a contact arm pack of the type above mentioned and decrease the separation between successive members to reduce the overall height of the pack.

According to the present invention, the metal members or plates are separated by annular ceramic spacers having hubs which fit into apertures in the members and through which the supporting bolts pass, the hubs serving to insulate the members from the bolts. Each member is cut away between the spacers along the major portion of a line passing through the bolt centers with adjacent members being cut away on opposite sides of the center line. With this arrangement, the spacing between overlying portions of the arms equals the distance between alternate members rather than the distance between successive members and there is an air gap between successive members in the space between the two stacks of ceramic insulators. The capacity effect between successive plates is, therefore, materially reduced and the spacing between the members may be lessened, thereby reducing the overall height of the contact arm pack. Furthermore, the ceramic spacers are less absorptive of moisture than other insulating materials so that there is less likelihood of leakage developing between successive strips by reason of moisture accumulating on the spacers.

Other objects, novel features and advantages of this invention will become apparent from the following specification and accompanying drawings, wherein:

Fig. 1 is a side elevation of a relay embodying the invention;

Fig. 2 is a plan view;

Fig. 3 is an end view of Fig. 1 looking from the right;

Fig. 4 is a section on the line 4—4 of Fig. 1;

Fig. 5 is a fragmentary section on the line 5—5 of Fig. 1; and

Figs. 6, 7, 8 and 9 are detail views of contact arms.

An L-shaped plate 10 has attached to one arm an iron core 11 enclosed by a wire coil 12 with the remaining arm of the L extending lengthwise of the coil. A second plate 13 is fixed to the last-mentioned arm of the member 10 and extends beyond the end of the coil opposite the remaining arm of the plate 10 and is provided with apertured lugs 14. A plate-like armature 15 extends across the free end of the core 11 and has apertured arms 16. A pin 17 extends through the apertures in the lugs 14 and arms 16 to pivotally attach the armature 15 to the plate 13. In the armature is adjustably mounted a bolt 18, one end of which is engageable with the adjacent end of the core 11. An arm 19 extends from the armature 15 longitudinally of the core and its end rests upon a stop 20 supported by the plate 13. The structure up to now described has been long in use and forms no part of the present invention.

On the plate 13 is supported a contact arm pack made up of several rigid and several flexible members. These members are separated from each other by spacers 21 composed of ceramic material and each having a hub 22 fitting into an aperture in one of the aforementioned members. Bolts 23 pass through the spacers 21 and are threaded into the plate 13 to hold said members in packed relation. The lowermost member 24 is a rigid contact arm and is of the configuration shown in Fig. 6. The next member 25 is a flexible contact arm and is of the configuration shown in Fig. 7. The third member 26 is a rigid contact arm and is of the same configuration as 24. The member 27 is a rigid contact arm and is of the configuration shown in Fig. 8. The member 28 is a flexible contact arm and is of the configuration shown in Fig. 9. The member 29 is a rigid contact arm and is of the configuration shown in Fig. 8. The member 30 is a rigid contact arm and is of the configuration shown in Fig. 7. The top member 31 is a flexible contact arm and is of the configuration shown in Fig. 6. The arms 24, 27 and 30 carry contacts 24a, 27a and 30a respectively on their upper faces only while the contacts 26, 29 and 31 carry contacts 26a, 29a and 31a respectively on their lower faces only. The arms 25 and 29 carry contacts 25a and 25b and 28a and 28b respectively on both top and bottom faces.

In Figs. 7 and 9, each of the members is provided with a body portion through which the bolts 23 extend and an offset flexible portion extending from a point near the left bolt and the

contact is attached to the free end of this portion. Between the apertures each member is cut away along the major portion of the line joining the aperture centers but on opposite sides of such center line. In Figs. 6 and 8, the member is provided with a body portion through which the bolts 23 extend and continues into an arm right-angled at its end and supporting a contact. Between the apertures the member of Fig. 8 is cut away similarly to the member of Fig. 7 and the member of Fig. 6 is cut away similarly to the member of Fig. 9. Thus, in the assembled contact pack, the metal between apertures in the successive members lies alternately on opposite sides of the center line as illustrated in Fig. 4 and the spacing between overlying portions equals the distance between alternate members rather than successive members. This arrangement serves to reduce the capacity effect between successive members.

A button 32 of insulating material is mounted on the free end of the arm 19 and engages the free end of a flexible metal arm 33 projecting from a member 34 contacting the member 25 and having apertures through which the bolts 23 pass, the member 33 being in electrical contact with and of generally similar shape to the member 25. A button 35 of insulating material is carried by the arm 25 and extends upwardly into engagement with the arm 28. A button 36 of insulating material is carried by the arm 31 and extends downwardly into engagement with the contact 28. Upon energization of the electromagnet, the arm 19 swings counterclockwise and by reason of engagement of the button 32 with the arm 33 moves the latter into engagement with the flexible portion of the member 25. Further movement of the armature results in upward movement of the contacts 25 and 25b and also of the contacts 28a and 28b as well as the contact 31a.

The structure described in the preceding paragraph is found in the known relays of the type to which the invention relates. The novelty of the present invention is centered in the contact arm pack per se.

It is of course understood that various modifications may be made in the structure above described without in any way departing from the spirit of the invention as defined in the appended claims. For example, while the spacers 21 have been disclosed as being composed of ceramic material, it is contemplated that the spacers may be composed of any inorganic insulating material having electrical and mechanical properties similar to steatite.

I claim:

1. In a relay, a plurality of parallel contact arms, a pair of supports extending through said arms in spaced relation and a pair of annular ceramic spacers between each pair of arms with one of said supports passing through each spacer, the adjacent arms being oppositely cut away between the spacers to reduce the capacity between said arms.
2. In a relay, a plurality of parallel contact arms, a pair of apertures in each arm, a pair of annular ceramic spacers between each pair of arms and having hubs located in said apertures and a support passing through each set of spacers, successive arms being alternately cut away along the major portion of a line passing through the centers of said apertures to reduce the capacity effect of the assembly.
3. In a relay, a plurality of parallel contact arms, a pair of supports extending through said arms in spaced relation and a pair of annular spacers between each pair of arms with one of said supports passing through each spacer, the adjacent arms being oppositely cut away between the spacers to reduce the electrical capacity between said arms and the spacers being composed of an inorganic insulating material having electrical and mechanical properties similar to steatite.
4. In a relay, a plurality of parallel contact arms, a pair of apertures in each arm, a pair of annular spacers between each pair of arms and having hubs located in said apertures, and a support passing through each set of spacers, successive arms being alternately cut away along the major portion of a line connecting the centers to said apertures to reduce the capacity effect of the assembly and said spacers being composed of an inorganic insulating material having electrical and mechanical properties similar to steatite.
5. In a relay, a plurality of parallel contact arms, a pair of supports extending through said arms in spaced relation, and spacing means insulating said arms from said supports and from each other, the adjacent arms being oppositely cut away between the supports to reduce the capacity between said arms.
6. In a relay, a plurality of contact arms, a pair of apertures in each arm, supports passing through each set of apertures, and spacing means insulating said arms from said supports and from each other, successive arms being alternately cut away along the major portion of a line passing through the centers of said apertures to reduce the capacity effect of the assembly.

JOHN H. HORMAN.
